UNITED STATES PATENT OFFICE

CLARENCE W. HUBBELL, OF NAUGATUCK, CONNECTICUT, ASSIGNOR TO REVERE RUBBER COMPANY, OF PROVIDENCE, RHODE ISLAND, A CORPORATION OF RHODE ISLAND

WATER TOY

Application filed July 7, 1930. Serial No. 466,069.

My present invention relates to water toys and more particularly to an improved stabilized water toy.

Water toys are at the present time made to simulate practically all forms of animal life, such as ducks, swans, horses, camels and the like, and one of the serious objections thereto, and which limits the use thereof to a great degree is the inability of such toys to remain in an upright or natural position when in the water. Where the toy is of any considerable size as where the toy simulates a horse or camel, the person using the same must be extremely agile in order to maintain the same in an upright position during the use thereof. Up to my present invention, no means has been devised for enabling such water toys to remain in upright position or be stabilized.

In my present invention, I have obviated the difficulties heretofore experienced, and have devised a form of stabilizing elements for inflatable water toys, and by means of which it is possible to float the toy in an upright or natural position on the water, and in which the stabilized elements may be utilized as foot rests in the larger size toys. My invention is particularly applicable for use in connection with water toys or animals resembling aquatic animals such as a duck or swan and the like, and in which it is desirable to have float in enclosed ponds, either natural or artificial.

In carrying out my invention, I associate with the body of the toy and on each side of the lower part thereof, inflatable pontoons or bilge keels, such pontoons or bilge keels being formed integral with the body or separate therefrom, as may be desired. Preferably, the inflatable pontoons or bilge keels are connected to the interior of the body of the animal so that inflating the animal causes a simultaneous inflation of the pontoons or bilge keels. This is the preferable construction, but I may substitute therefor a pontoon or bilge keel having no connection whatever with the interior of the body of the animal and each pontoon or bilge keel therefore may be provided with means for permitting in-

flation thereof independently of the body and of each other.

The object of my invention, therefore, is an improved stabilized inflatable water toy.

In the accompanying drawings illustrating 55 preferred embodiments of my invention;

Figure 1 is a perspective view of a swan toy to which my improved invention has been applied;

Figure 2 is a sectional end elevation on the 60 line 2—2 of Fig. 1.

Fig. 3 is a perspective view of the body portion of the animal illustrated in Fig. 1, showing one of the pontoons or bilge keels in perspective sectional elevation;

Fig. 4 is a side elevation of a land animal such as a camel to which my invention has been applied, and

Fig. 5 is a similar view, but the animal to which the invention has been applied is a 70 horse.

Referring to Figs. 1, 2 and 3, 10 designates the body portion of an inflatable toy built to represent a swan or other aquatic animal, the rear portion of the body 10 being provided with a valve 11 which may be connected to any suitable source of air or gas supply and by means of which the body 10 of the animal may be inflated, as is usual. It is to be understood, of course, that the entire animal is 80 made of resilient material such as rubber.

Referring to Fig. 2, it will be noted that on either side of the body of the animal adjacent to the lower portion thereof are attached pontoons or bilge keels 12. These pontoons 85 or bilge keels 12 when inflated, being of proper size when the size of the body 10 is taken into consideration to maintain the body 10 floating in an upright position, that is with the neck 13 and head 14 of the animal extending upwardly and in the normal position of such an animal. As the pontoons or bilge keels 12 are attached to the body 10 in Figs. 1, 2 and 3, it will be noted that the interior of such pontoons communicates with the interior of the body 10 by a plurality of perforations 15, so that when air or other gaseous fluid is pumped into the body 10 through the valve 11, the interior of the pontoons or bilge keels 12 will be simultaneously inflated and 100

the pressure within the pontoons or bilge keels is the same as the pressure within the body 10. I may, however, provide each of the pontoons or bilge keels 12 with its own valve 5 similar to the valve 11, but as the preferred form is shown in the drawings, I have not illustrated the alternative method of applying air or other fluid to the pontoons 12.

In Fig. 4 is illustrated an inflatable toy 10 16 to simulate a camel which has attached to the body thereof on each side, and adjacent the bottom, pontoons or bilge keels 17 similar to the pontoons or bilge keels 12 in Figs. 1, 2 and 3.

15 In Fig. 5 is illustrated an inflatable horse 18 provided with pontoons 19 arranged as in the case of the camel shown in Fig. 4. It is customary to make figures of camels or horses relatively large and it is possible to actually 20 ride such animals in the water. Not only will such animals remain in an upright position in the water because of the presence of the pontoons or bilge keels 17 and 19, for example, but a person riding the same may utilize 23 such pontoons or bilge keels for supports for their feet. Obviously, an inflatable water toy may be built to simulate any animal; and my invention may be applied thereto. It is believed, however, that the drawings accompanying the present application are sufficient 25 to a thorough understanding of the invention.

Having thus described my invention, what I claim and desire to protect by Letters Patent is:

1. In a stabilized water toy, the combination with an inflatable hollow body, of inflatable pontoons of smaller displacement than the body arranged on either side of and below 45 the middle of the body and extending laterally downward at an angle, and means permitting the body and pontoons to be inflated simultaneously and to the same degree.

2. In an improved inflatable water toy, the combination with an inflatable body, of a stabilizing pontoon attached thereto on either side thereof adjacent the submerged portion thereof, and extending along the major portion of the length of the body, and passages 50 extending from the body to the pontoons whereby the body and pontoons may be simultaneously inflated.

Signed at Naugatuck, county of New Haven, State of Connecticut, this first day of July, 1930.

CLARENCE W. HUBBELL.
